POLE-CHANGER.

1,162,992.

Specification of Letters Patent.

Patented Dec. 7, 1915.

Application filed August 23, 1906. Serial No. 331,701.

To all whom it may concern:

Be it known that I, CHARLES J. ERICKSON, a citizen of the United States of America, and resident of Chicago, Cook county, Illinois, have invented a certain new and useful Improvement in Pole-Changers, of which the following is a specification.

My invention relates to pole changers or devices by which a battery current can be converted into an alternating current. Devices of this character are used, for example, in telephone systems in ringing the subscribers' bells, and more especially for selectively operating the bells on a party line. This is for the reason that a pole changer can be readily adjusted to vary the frequency of the current, thus making it possible to economically supply alternating currents of different frequencies for selectively operating the bells on a party line. It will be understood, however, that my improved pole changer can be employed for any suitable or desired purpose.

In certain respects my present invention is in the nature of an improvement on the pole changer disclosed in my prior application Serial No. 330,192, filed August 11, 1906. In my said prior application the operating circuit for energizing the electro-magnet is independent of or distinct from the generating circuit which includes the primary of the transformer or induction-coil, although, of course, both circuits include the battery or some portion thereof. With my present invention, however, the said two circuits are not only independent of and distinct from each other, but in addition the operating or energizing circuit for the electro-magnet does not include the battery or any portion thereof, but does include the secondary of the transformer or induction-coil. With this arrangement the battery current is not employed for energizing the operating magnet of the pole changer. In this way the pole changer will, I find, operate efficiently on less current than those heretofore employed.

In the accompanying drawings Figure 1 is a diagram of a pole changer embodying the principles of my invention. Fig. 2 is a front elevation of the said pole changer. Fig. 3 is a horizontal section on line 3—3 in

Fig. 2. Fig. 4 is a detail plan view of the mounting or yoke which supports the armature and pendulum.

Referring to Fig. 1 my improved pole changer comprises an operating electro-magnet A provided with an armature B, which latter is preferably mounted as hereinafter described. The electromagnet and its armature are polarized by the permanent magnet M (Fig. 2) in the well-known manner in which ordinary alternating current ringer magnets are polarized. The armature B is provided with a downwardly-extending pendulum b having an adjustable weight b¹. This weight can be moved up and down to vary the frequency of the current produced by the pole changer. The battery C is divided into sections c and c¹. The middle point or connection c² between the two battery sections is connected with one terminal of the transformer or induction-coil primary D, the other terminal of this primary winding being connected directly with the said armature B. The said pendulum also carries a double ended switch contact b² adapted to vibrate between the stationary contacts E and F. These two stationary contacts are connected with the opposite poles of the battery C, as shown in Fig. 1. The secondary winding G of the said transformer or induction-coil is connected in series with the windings or energizing coils of the electro-magnet A, this circuit also preferably including a condenser H.

With this arrangement it will be seen that the energizing coils or windings of the electro-magnet A are connected in parallel with the telephone or other line I across which is bridged the call-bell J. In this way the alternating current produced in the secondary G is supplied partly to the said operating magnet A and the balance goes to the line for operating the call-bell.

To start the pole changer it is only necessary to swing the pendulum to one side, so as to close a circuit in one direction through the primary D. Suppose, for example, that the pendulum is pushed to one side until the contact b² touches the stationary contact E. Current then flows in one direction through the primary D, with the result that a dis-

charge takes place through the condenser H and secondary G, and through the windings of the magnet A. The windings of the magnet A are so connected that current flowing through them in this direction strengthens the left-hand pole of the magnet and weakens the right-hand pole, with the result that the left-hand end of the armature B is drawn downward, carrying the contact b² 10 out of engagement with the stationary contact E and into engagement with the contact F. As a result of the engagement of the contacts b² and F a flow of current is set up in the primary winding D in the opposite direction, which induces a current in the secondary winding G which is in a direction opposite to the current induced therein when the contact b² engages the contact E. This current flows through the 15 windings of the magnet A in a direction opposite to the first impulse described, and attracts the armature B in the opposite direction, which again reverses the current in the primary winding D. Thus an alternating 20 current is supplied through the windings of the magnet A, with the result that its armature and pendulum are kept vibrating, and with the further result that the desired supply of alternating current is maintained in 25 the line circuit. It will be understood, of course, that the resistance of the magnet A can be adjusted in such manner as to give the best results, as is also true of the capacity of the condenser H. In other words, 30 the resistance of the circuit including the windings of the magnet A should be such that only just enough current is admitted to efficiently energize the magnet.

It is obvious, of course, that in practice 35 suitable switches may be employed for controlling the flow of current to a line circuit.

Referring to Figs. 2 to 4, inclusive, it will be seen that the said armature and pendulum are mounted upon a spring K, 40 which latter is in turn mounted upon a yoke L applied to the cores of pole-pieces of the said electro-magnet. This spring, it will be seen, has its end portions secured to the said yoke, and is arranged at right angles to the 45 length of the latter. With this arrangement the said spring is given a torsional twist by the vibration of the armature and pendulum. The contacts E and F consist preferably of 50 springs which are mounted on brackets e and f, and which normally rest against the stationary springs or contacts e¹ and f¹, the latter being also mounted upon the said posts or brackets. The stationary contacts or adjustable screws e² and f² bear against 55 the contacts e¹ and f¹, as shown in Fig. 3, and in this way the vibration of the pendulum is subject to very little resistance. When 60 the pendulum strikes the spring F the circuit is then from this spring through the adjacent spring f¹, thence through the screw

or adjustable contact f² to the bracket f, and then to the binding post 1, which latter is connected with one pole of the battery, as shown in Fig. 1. When the pendulum strikes the spring E, the circuit is then from 70 this spring through the spring e¹ to the screw or adjustable contact e², thence through the bracket e to the binding post 2, which latter is connected with the other pole of the battery, as shown in Fig. 1. Any 75 suitable binding post arrangement can be employed for connecting the secondary of the transformer in series with the coils or windings of the electro-magnet, and for connecting the middle point of the battery in 80 series with the primary of the transformer and the pendulum of the pole changer.

What I claim as my invention is:—

1. In a pole changer apparatus, the combination of an electromagnet, a divided battery, a local battery circuit, a vibrating pendulum with means for accurately adjusting its frequency, said pendulum operated by the electromagnet and provided with means for reversing the flow of current in said 90 circuit, said means comprising a spring provided with end and intermediate points of connection, a support engaging the said end points of connection on the spring, and means for securing the pendulum to the intermediate point of connection on the spring, said spring and pendulum included in said 95 circuit, whereby the spring is first in series with one division of said battery and then in series with the other division thereof. 100

2. In a pole changer apparatus, the combination of an electromagnet, a divided battery, a local battery circuit, means operated by the magnet for reversing the flow of current in said circuit, said means including a vibratory member with means for accurately 105 adjusting its frequency, a stationary supporting member, and a spring having its ends secured to one of said members and its middle portion secured to the other of said 110 members, said spring and pendulum included in said circuit, whereby the spring is first in series with one division of said battery and then in series with the other division thereof. 115

3. In a pole changer apparatus, an operating electromagnet, a local battery circuit, vibratory means operated by the magnet for reversing the flow of current in said circuit, a transformer secondary winding connected 120 in series with the coil of said magnet, the primary of said transformer being in said local circuit, and a divided battery having its middle part connected with said primary. 125

4. In a pole changer apparatus, the combination of an electromagnet, a polarizing permanent magnet associated therewith, a battery, a transformer, a vibrating pendulum and connections for reversing the flow of battery current through the primary of 130

the transformer, and means for connecting the coil of said electromagnet in series with the secondary of the transformer.

5. In a pole changer apparatus, the combination of an electromagnet, a polarizing permanent magnet associated therewith, a battery, a transformer, a vibrating pendulum and connections for reversing the flow of battery current through the primary of said transformer, and means for connecting the coil of the electro-magnet in series with the secondary of the transformer, the said battery being divided into sections and having its middle point connected with one terminal of the said transformer primary.

6. In a pole changer apparatus, the combination of an operating magnet, a polarizing permanent magnet associated therewith, a pendulum operated by the magnet, a battery, a transformer, connections by which the vibration of the pendulum reverses the flow of current in the primary of the transformer, a line circuit including the secondary of the transformer, and a local secondary circuit including the coil of said operating magnet.

7. In a pole changer apparatus, the combination of an operating magnet, a polarizing permanent magnet associated therewith, a pendulum operated by the magnet, a battery, a transformer, connections by which the vibration of the pendulum reverses the flow of current in the primary of the transformer, a line circuit including the secondary of the transformer, a local secondary circuit including the coil of said operating magnet, and a condenser in said local circuit, said battery being divided into sections and having its middle point connected with one terminal of the transformer primary.

8. In a pole changer, an electromagnet, a polarizing permanent magnet associated therewith, a pendulum vibrated thereby, spring contacts alternately engaged by the pendulum, resting contacts for said spring contacts, and adjustable contacts engaging said resting contacts.

9. In a pole changer apparatus, the combination of an electromagnet, a battery, a transformer, a vibrating pendulum with means for accurately adjusting its frequency and connections controlled thereby for reversing the flow of battery current through the primary of the transformer, and means

connecting the electromagnet in series with the secondary of the transformer, whereby said electromagnet is energized by the alternating current in the secondary.

10. In a pole changer apparatus, the combination of an electromagnet, a battery, a transformer, a vibrating pendulum with means for accurately adjusting its frequency, and connections controlled thereby for reversing the flow of battery current through the primary of the transformer, means connecting the electromagnet in series with the secondary of the transformer, the said battery being divided into sections and having its middle point connected with one terminal of the said transformer primary, said magnet being thereby energized only by the alternating current in the secondary.

11. In a pole changer apparatus, the combination of an operating magnet, a pendulum with means for accurately adjusting its frequency, said pendulum operated by the magnet, a battery, a transformer, connections by which the vibration of the pendulum reverses the flow of current in the primary of the transformer, a line circuit including the secondary of the transformer, a local secondary circuit including the said operating magnet, said magnet being thereby energized only by the alternating current in the secondary.

12. In a pole changer apparatus, the combination of an operating magnet, a pendulum with means for accurately adjusting its frequency, said pendulum operated by the magnet, a battery, a transformer, connections by which the vibration of the pendulum reverses the flow of current in the primary of the transformer, a line circuit including the secondary of the transformer, a local secondary circuit including the said operating magnet, a condenser in said local circuit, said battery being divided into sections and having its middle point connected with one terminal of the transformer primary, said magnet being thereby energized only by the alternating current in the secondary.

Signed by me at Chicago, Cook county, Illinois, this 18th day of August, 1906.
